(57) **CLAIM**

The ornamental design for a flow channel for drip irrigation with biased cavity, as shown.

DESCRIPTION

FIG. 1 is a top plan view of a “flow channel for drip irrigation with biased cavity” showing our new design, a typical hose being indicated in broken line and forms no part of the claimed design;

FIG. 2 is a side elevational view thereof; and,

FIG. 3 is a left hand end view thereof.
